United States Patent Office

Des. 229,144

Patented Nov. 13, 1973

229,144

TABLE BASE

John H. Furber, Columbus, Ohio, assignor to J. H. Furber
Company, Columbus, Ohio

Filed Nov. 24, 1971, Ser. No. 202,064

Term of patent 14 years

Int. Cl. D6—06

U.S. Cl. D6—194

The sole figure is a perspective view of a table base, showing my new design.

I claim:

The ornamental design for a table base, as shown and described.
